ATTORNEY

UNITED STATES PATENT OFFICE

ERNEST J. ALLEN, OF LONG ISLAND CITY, NEW YORK, ASSIGNOR TO PARROTT DRY PROCESS STREET CLEANER COMPANY, INC., OF NEW YORK, N. Y., A CORPORATION OF DELAWARE

STREET-CLEANING BRUSH

Application filed May 14, 1928. Serial No. 277,635.

This invention relates to street cleaning machines, and my improvements are directed to a novel form of expandible brush that is revolubly mounted in a machine of the character indicated, and capable of enlargement in its circumference to compensate for wear of its bristles.

Also my invention comprises the employment of means whereby the brush may be expanded variably at its opposite ends, thereby enabling a greater degree of brush expansion at the end near the street curb, for the purpose of more thoroughly sweeping along the depressed or gutter portion of the street.

Still further my invention comprehends the structure of an expandible brush composed of longitudinal segments having radial telescopic means of adjustment relative to a common hub, combined with lengthwise separated expanding means operable either in uniformity or in different degrees.

Other features and advantages of my invention will hereinafter appear.

25 In the drawing:

Figure 1 is a side sectional elevation of a brush provided with my improved means of expansion.

Fig. 2 is a partial similar view, showing the brush segments expanded, and

Fig. 3 is a section on the line 3—3 of Fig. 2.

In said figures let 1 indicate a shaft revolubly mounted in bearings 2, 2 carried by hangers 3, 3 that are suitably supported by the frame (not shown) of a street sweeping machine.

Secured in spaced relation upon shaft 1 are the hub members 5, 5 each having connected thereto a series of tubular radial spokes 6, adapted respectively to receive rods 7 that are oscillably carried by the head portions 8 of brush segments having the bristles 9, said brush segments all being of full brush length.

45 It will be noted that with the rods 7 fully ensheathed within the tubular spokes 6, as shown in Fig. 1 the brush segments are contracted to the smallest diameter of the brush, and that with said rods 7 extended as shown 50 in Figs. 2 and 3 the brush segments are there-

by expanded to increase the diameter of the brush.

The brush expanding means consists of sets of links 10 between the brush segments and a collar 11 that is slidable upon shaft 1, each link having pivotal engagement with a lug 12 upon the head 8 of a brush segment and with a lug 13 upon collar 11. There is a collar 11 upon each end portion of shaft 1, outside the respective hub members 5, 5, and the links 10 in each set are inclined outwardly toward their collars. A stop 14 upon the shaft, between each hub 5 and collar 11, limits the inward travel of said collar, thereby determining the degree of expansion permitted the brush segments.

The shaft 1, at each end portion, beyond the collars 11, is provided with a screw thread 15, and a hand wheel 16 engages said thread by means of its hub portion 17, which hub portion is in revoluble engagement with the slidable collar 11. Hence, upon turning the hand wheel 16 its axial movement is communicated to collar 11, thereby having the effect, through links 10, of moving the brush segments radially, to expand or contract the brush according to the direction of rotation imparted to said hand wheel.

It will be understood that as the two sets of expanding means are separately operable with respect to the opposite end portions of the shaft, in consequence the brush segments at one end may be expanded to a greater extent than the brush segments at the other end, and further that in this differential expansion of the brush a somewhat loose fit of the rods 7 in the tubular spokes 6 thereby permits the brush at its more expanded end to assume a conoidal form that adapted it to have close sweeping contact in a gutter-like depression of the road.

Variations within the spirit and scope of my invention are equally comprehended by the foregoing disclosure.

I claim:

1. In a street sweeping machine, in combination, a revoluble shaft, an expandible brush composed of longitudinal segments, telescopic engaging means between said shaft and segments, collars slidably carried by said

shaft, links connecting said collars and said segments and means borne by said shaft and cooperating with said collars to move said segments radially to expand said brush.

5. 2. A brush for street sweeping machines comprising a series of radially disposed longitudinal brush segments, a central shaft, tubular spokes extended radially from said shaft, rods carried by said brush segments, 10 said rods having loose telescopic engagement with said spokes, a collar slidably mounted upon each end portion of said shaft, links connecting each of said collars to said segments, and a hand wheel threadedly carried 15 by each end portion of said shaft, each wheel being selectively operable and adapted to co-operate with the respective collars whereby said brush may be expanded variably at its opposite ends.

20. New York, May 8th, 1928.

ERNEST J. ALLEN.
